UNITED STATES PATENT OFFICE

2,045,490

ENVELOPE MACHINE

Lewis C. Pearce, Cleveland, Ohio, assignor to The Standard Envelope Manufacturing Company, Cleveland, Ohio, a corporation of Ohio

Application September 4, 1931, Serial No. 561,244

7 Claims. (Cl. 93—61)

This invention, relating, as indicated, to an envelope machine, is more particularly directed to an apparatus in which an envelope may have printed matter placed thereon, and then have a fastener attached thereto, after which a patch is applied to the flap of said envelope.

An outstanding difficulty had with the envelope machines of the prior art is that the clasp or fastener mechanism has to operate entirely too fast. In some instances the ratio is 4 to 1, and this rapid speed of the fastener mechanism causes numerous breakdowns and renders the machines generally inefficient.

Another disadvantage of most of the patented envelope machines is that no wide range in sizes of envelopes could be taken care of by one machine.

A further disadvantage of prior machines is that most of them employ gripping means for holding the envelopes while the fasteners are attached, and such means have proved objectionable because the envelopes, being of paper, may be easily torn or mutilated, thus incurring a large amount of waste.

The inefficiency of previous machines of this type has been proven by the fact that in almost any envelope plant a number of such machines will be seen which have been junked, and the plants have used hand labor to feed the envelopes to the fastener applying mechanism. The average number of envelopes which can be operated upon by hand a day is 16,000 whereas in my improved machine 32,000 envelopes can have printed matter placed thereon, fasteners attached, flaps perforated and patches applied to the portion of an envelope surrounding said perforation.

Accordingly, it is an object of the present invention to provide a machine which is free from the above disadvantages and one which is just as capable of operating upon large envelopes as well as small envelopes.

Throughout the specification and claims it will be seen that the subject-matter of this application is directed to a means for applying a fastener to an envelope but, of course, it will be understood that the fastener may just as well be applied to other similar articles, and that an envelope is used only for convenience of description.

The annexed drawings and the following description set forth in detail certain mechanism embodying the invention, such disclosed means constituting, however, but one of various me-

chanical forms in which the principle of the invention may be used.

In said annexed drawings:—

Fig. 1 is a front elevation.

45

Fig. 23 is a detail view of a part of Fig. 20.

Fig. 24 is a perspective view taken from the rear of the fastener slot or conduit.

Fig. 25 is a similar view taken from the front.

50

Fig. 26 is a detail view showing the fastener applying mechanism removing a fastener from the fastener slot.

Fig. 27 is a vertical section of the end of the fastener applying mechanism.

55

Fig. 28 is a perspective view of a fastener after it has been perforated.

Fig. 29 is a vertical section on line 29—29 of Fig. 27 showing the fastener holder in retracted position.

Fig. 30 is a detail view taken on the line 30—30 of Fig. 29.

Fig. 31 is a view similar to Fig. 29 showing the fastener applying mechanism in operative position.

Fig. 32 is a plan view of an individual envelope prior to the application of the fastener thereto.

Fig. 33 is a view similar to Fig. 32 showing the fastener applied.

Fig. 34 is a plan view of an individual fastener. Fig. 35 is a side elevation of a fastener.

Fig. 36 is a view similar to Fig. 34 after the fastener has been perforated.

Fig. 37 is an enlarged section taken on line 37—37 of Fig. 36.

Fig. 38 is a view similar to Fig. 32 showing an individual envelope with a patch and fastener applied thereto.

Fig. 39 is an enlarged sectional view taken on the line 39—39 of Fig. 38.

Fig. 40 is a plan view of a portion of the tape from which the patches or reinforcements are made.

Fig. 41 is a side elevation of Fig. 40.

Fig. 42 is a plan view of an individual patch.

Referring now to the drawings, and especially to Figs. 1 and 2, it will be seen that my improved apparatus consists of power means generally designated at A and adapted to operate the entire mechanism by means of belts, chains, sprockets, etc. A magazine is shown at B, which is the initial feeding means for the envelopes to which the fasteners are to be attached. Immediately adjacent the envelope feeding means is a printing press C, and this press has its outlet in line with a carrier wheel D, in such a manner that envelopes which have been printed are received by the carrier wheel. A fastener feeding means is illustrated at E and a fastener applying mechanism F is shown between the fastener feeding means E and the carrier wheel D. A patch applying mechanism is shown at G, and a fastener anvil is shown at H. A means of ejecting the envelopes from the carrier wheel is generally designated at I, and at the extreme right hand portion of Fig. 1 a conveyor is illustrated for carrying the finished envelope to any desired point.

Having described each of the sub-assemblies of the whole apparatus briefly, I will now describe each assembly more in detail.

POWER MEANS

"A"

Referring now more specifically to Figs. 1, 2 and 8, it will be seen that a base 1 is provided upon which a motor support 2 rests, the base 1 serving for the entire apparatus. A motor 3 is illustrated, which has a shaft 4 upon which pulleys are mounted, the outermost pulley being smaller than the innermost. The inner pulley has a belt 5 encircling it and this belt also encircles a pulley 6 fixed to a shaft 7 of an air pump 8, the inlet 9 of such pump having a conduit 10 connected thereto which in this instance may be a rubber hose, and the outlet 11 of such pump being opposite to the inlet 9. Briefly, the function of the air pump is to provide a means of suction to remove the lowermost envelope in a stack of envelopes in the magazine, and to feed the envelopes to a printing press.

The outer smaller pulley on the shaft 4 has a belt 12 which encircles it and a pulley 16 fixed to a shaft 14, this last named shaft having a smaller pulley 13 located inwardly of the pulley 16. A belt 17 transmits power from the pulley 13 to the pulley 18 mounted on shaft 19, this shaft 19 being the main source of power for most of the various mechanisms, through the medium of the various sprockets and cams shown in Fig. 8.

A means of applying and releasing the power is shown consisting of a lever 26 having a handle 25, the lever being fixed by means of a set screw 24 to a transverse shaft 27, the latter shaft extending the full width of the apparatus and having connected thereto at the opposite end a link 28.

This link 28 is connected to another link 30 by means of a pivotal connection 29 and the link 30 is in turn connected to an arm 32, the last named arm being fixed to a shaft 33. The shaft 33 has another arm 34 extending in a direction opposite to that in which the arm 32 extends and the said arm 34 has a bent portion 35 upon which the idle roller 36 is rotatably mounted. It will be obvious that when the lever 25 is moved in a clockwise direction as viewed in Fig. 2, the link 28 will likewise move in a clockwise direction and the idle roller 26 will release the tension on the belt 17 so that all movement of the shaft 19 ceases. A locking means 37 is shown, which maintains the links 28 and 30 in alignment, thus maintaining the idle pulley in operative relation with respect to the belt 17.

ENVELOPE FEEDING MEANS

"B"

The envelope feeding means is generally designated at B and is to be seen at the extreme left hand portion of Fig. 1, details of which are shown in larger proportions in Figs. 3 and 4. The magazine 55 is supported on a frame which in this instance comprises uprights 41, 42, 44 and 45, all of which are attached to the base 1. The uprights 41 and 42 have a longitudinal connecting member 43, and as will be seen, the frame consists of pipe sections, but of course may be made of any suitable material. At the opposite side of the apparatus there is another longitudinal support 46 joining the uprights 44 and 45, and at the extreme end an upper transverse member 47 connects the end uprights 41 and 44.

An envelope magazine is shown consisting of a bottom plate 55 and vertical sides 56 and 57, these vertical sides being adjustable by means of the locking members 58, 61, 62 and 63 which engage the projections on said vertical members, one of which is shown at 59. Obviously, the magazine can be modified quickly and easily for various sizes of envelopes, thus insuring efficient operation in that each envelope is accurately guided into position.

In Fig. 3 it will be seen that the envelopes are piled in a stack in the magazine and that the lowermost envelope in said stack has one of its ends resting on pins 118 adjacent a suction cup 50, this cup 50 being secured in an arm 51 by means of the arm engaging the rigid section 49, this section having the flexible air hose 48 attached to its end. The arm 51 is fixed to a shaft 68, and this shaft is movably supported by a pair of arms 52 and 52'. Another arm 53 is fixed to the shaft 68, and this arm has a spring 54 which exerts a pull thereon, and likewise tends to pull the suction cup to the left as shown in Fig. 3. The arm 53 has another

connection extending in a direction opposite to that of the spring 54, and this connection is in the form of a link 111, movement of such link tending to pull the suction cup 50 in a downward direction.

The means by which the link 111 is moved comprises a sprocket 66 mounted on a transverse shaft 91, there being a gear 64 fixed to said shaft at its opposite end. This gear 64 meshes with a gear 65 on transverse shaft 92, and this shaft has a cam 116 mounted thereon which engages a roller 107 mounted at one end of a lever 108, this lever being fixed to another transverse shaft 91. Also, mounted on shaft 91, but slightly removed from the plane of lever 108, is another lever 109 having a pivotal connection with the link 111 at pin 110. Obviously, movement of the shaft 91 imparts rotation to the shaft 91 through the action of the cam 116, and in turn the link 111 will move in a clockwise direction as viewed in Fig. 3, thus feeding the lowermost envelope from a stack of envelopes downwardly along the vertical guide 106.

A means of preventing the envelope which has been sucked downwardly from returning to its original position is provided in the form of bent levers 74 and 75 having rollers 77' and 77 thereon, respectively, movement of which is so timed that as the envelope reaches its lowermost position the said rollers 77' and 77 which have been retracted again assume the position shown in Fig. 3, and now the rollers grip the envelope by means of engagement with the discs 117 and 117'. The lever 74 is fixed to a transverse shaft 73 and movement is imparted thereto by means of the cam 112, which engages the roller 113 on the lever 114. The cam 112 is mounted on the transverse shaft 92, rotation of which is received in a manner hereinbefore described. The roller 113 is maintained in engagement with the cam 112 by means of a spring 79 engaging the arm 78 fixed to the shaft 73. Inspection of Figs. 2 and 3 reveals that a reciprocation of roller 76 is obtained by the action of cam 112, lever 114, and shaft 73.

The vertical guide 106, which in this instance is a circular member 50 so as to offer least resistance to movement, is maintained in fixed position by means of the arm 104 which is held to the fixed shaft 103 by the locking member 105. Further guide members are provided in the rods 100 which extend diagonally so as to engage the edges of the envelopes, thus assuring further that the envelope will be accurately guided on to the belt. The diagonal guide members are held to the fixed shaft 73 by the locking members 102.

The diagonal guide members 100, just referred to, have pins 118 received in their lower ends so as to provide a separator as well as a horizontal support just prior to gripping of the envelope between the rollers and discs. Of course, these pins project out only a very small distance in order to offer the least resistance possible to feeding, but it will be readily appreciated that each envelope is efficiently separated from the stack. After being separated the envelope travels over the belts 88 and under a series of ball bearings contained in the cages 16. Such construction provides an accurate means of transferring the envelopes, yet one in which the effects of friction are minimized.

The mechanical movement of the suction cup 50 has been described, and the means by which

intermittent suction is obtained is shown in the rotary valve 21 operated in conjunction with the printing press, and having an inlet 20 to which the flexible hose 10 is attached, and an outlet 22 to which the flexible tubing 48 is attached.

5

PRINTING MEANS

"C"

The printing means is best illustrated in Figs. 3 to 6 inclusive, and is actuated by a sprocket 120 fixed to the shaft 19, (Fig. 8), there being a chain 122 extending from said sprocket to another sprocket 121 fixed to the shaft 123. This shaft 123 extends inwardly and has mounted thereon substantially at its mid-portion an element 173 which has a type engaging face 174, which as shown, is adapted for printing a small amount of printed matter on the envelopes, but which may be obviously modified to print any amount desired.

A gear 124 is mounted on the shaft 123, and this gear meshes with a pinion 125 mounted on the shaft 126, this shaft having an inking roller mounted thereon. Another pinion 127 meshes with the pinion 125 and this latter pinion is mounted on the shaft 128 upon which a second inking roller is mounted. The latter pinion meshes with the gear 129 mounted on the shaft 130. The gear 129 meshes with the pinion 131 which is mounted on the shaft 133, this shaft having a sleeve 132 mounted thereon to which another inking roller 152 is secured.

Sliding movement of the inking roller 152 is obtained by engagement of the eccentrically mounted plate 151 with the collar 150 on the sleeve 132, the plate 151 being fixed to the shaft 130 so that rotation of the shaft 130 will rotate the inking roller 152 and slide it transversely in engagement with the inking rollers 153 and 154. The inking roller 154 is mounted on shaft 155 which is received in trunnions 156 and 157, these trunnions being mounted upon a shaft 158, there being a lever 148 fixed to said shaft and a spring 149 which tends to maintain the roller 154 in engagement with the roller 159. The roller 154 oscillates back and forth and in this manner transfers ink from the initial inking roller 159 to one of the intermediate inking rollers 152. Of course, to obtain such oscillation the resistance offered by spring 149 must be overcome and this is achieved by engagement of the pin 115 on the connecting rod 180, with the spring rocker arm 148. The initial inking roller 159 receives the ink, or other coloring matter, from the container 162 and is intermittently rotated by means of a spur wheel 184. Intermittent movement of the spur wheel 184 is obtained from the cam 190 fixed to the shaft 130 and engaging a roller 189 on the forked end of a connecting rod 180, this connecting rod having a pivotal connection 181 with a small link 182 upon which a dog 183 is mounted so as to engage the spurs on the spur wheel 184. The dog is held in constant engagement through the lever 185 by the spring 186, this spring being connected to the pin 187 mounted on the supporting plate 146.

The ink, or coloring matter, is first received upon the intermittently rotated roller 159, after which it is transferred to roller 154, which is the oscillating roller. Upon oscillation of the roller 154 the roller 152 is coated with coloring matter and this coating is transferred evenly and smoothly to another intermediate inking roller 153 by rotation of said roller as well as move-

75

ment in an axial direction. The last named roller 152 revolves in contact with a fourth inking roller shown supported on the shaft 128, and finally this roller contacts two other rollers, 166 and the roller supported on shaft 126, which, in turn, ink the type.

One of the final inking rollers 166 is mounted on a shaft 165 which revolves in arms 164, said arms being adjustably fixed to a shaft 163.

10 The cylinder which engages the lower surface of the envelope N as it is being printed, is mounted on the shaft 135, movement being imparted to this shaft by means of the gear 134 which meshes with the gear 126. A sprocket 136 is fixed to the shaft 135, and this sprocket has a chain 137 engaging it and the two smaller sprockets 138 and 165, respectively, there being a tensioning roller 169 mounted on the arm 148, the said arm being secured to the shaft 170. The shaft 94, which obtains its movement from the sprocket 138, has a pinion thereon in mesh with a gear 140 mounted on the shaft 141 to which a segmental cylinder 142 is likewise attached.

20 A belt 86 is provided for the purpose of conveying the envelope from the magazine to the printing press, and this belt encircles the rollers 87, 88, 89 and 90, these rollers being mounted on the shafts 91, 92, 93 and 94, respectively. It will be understood that the belt may have a variable width or may consist of a number of narrow belts. A pair of supports 214 and 215 are provided so that the belts may serve only to move the envelopes and will not have to support any weight.

25 The finger 200 is a feeler which acts to prevent ink on the type from coming in contact with the roller 119 in the event that no envelope is caused to pass between the said roller and the type. The advantage derived from such a construction is of paramount importance because if 30 the roller 119 becomes smeared with ink, a number of envelopes will have to be wasted for the reason that they in turn will become smeared. The finger 200 is fixed to lever 202, and the said finger normally rests on top of an envelope as 35 shown in Fig. 6. The lever 202 in turn normally engages an arm 203 which is fixed to a lever 204, said lever having a cam roller 206 mounted upon a pin on its innermost side. This cam roller 40 engages an eccentric disc mounted on the shaft 135, but is normally disengaged due to the length 45 of arm 203 which with the lever 202 holds the cam in inoperative position. However, if for any reason an envelope fails to pass under the finger 50 200, the weight of said finger will cause it to 55 descend and move the lever 202 in a counter-clockwise direction as viewed in Fig. 6, it being understood that the spring 209 is of light construction, thereby easily permitting such movement. As soon as the lever 202 rides over the 60 prong on arm 203, this arm will tend to rise due to the action of spring 209, and then the cam roller will ride upon the eccentric disc 207. The 65 brake 217 will then be caused to momentarily stop the roller 119 at a predetermined point, and this point 218 on the roller 119 will be recessed so that the type will not engage the outer surface of the roller 119. In Fig. 6, the normal 70 position of the finger 200 and the braking mechanism is illustrated while in Fig. 3 the roller 119 is shown in locked position with the recess 118 uppermost. The levers 203 and 204 are maintained in engagement with the cam 207 by means of the spring 209 attached to the lower cross bar 75 210, and this lower cross bar has mounted there-

above a similar bar 211 whereon the means 213 for supporting the lever 202 is shown.

A pair of fingers are illustrated at 216 and 216', these fingers being attached to and moving with a small shaft 198, movement of which is obtained by the links 197 and 193. The purpose of the fingers 216 and 216' is to provide a means of registering an envelope just prior to its being printed, that is, accurately aligning the envelope in order that the printed matter will be placed in the desired spot on the envelope. By correlating the movement of the fingers with that of the roller 119 and the type this may be accomplished. The fingers are bent at their free ends in order to lightly grip the envelope and retain it momentarily, after which the envelope passes between the segmental disc 142 and is ready for printing. The operating links 197 and 193 have a pivotal connection 196, and the end of the link 193 is forked to engage the transverse shaft 130, 20 upon which a cam 191 is mounted for engagement with the roller 192 rotatably mounted on the link 193. Constant engagement of the roller with the cam is assured by the provision of the spring 194.

25 A means of pressing the envelope against the cylinder 119 is provided in the idle roller 172 mounted on the bell crank 175, which in turn is pivoted to the arm 171, such engagement being maintained by the spring 179 engaging one end 30 of the said bell crank. A slight pressure is obtained between the idle rollers 177 and 178 by pivoting the supporting arm 176 on the arm 171, and attaching a spring 178 to the arm 176.

CARRIER WHEEL
"D"

35 The mechanism describing the feeding of the envelopes to the printing press and the placing of printed matter thereon has been described 40 and now the envelope is ready to have the fastener applied thereto. As a means of receiving the envelope from the printing press and transferring it to the fastener applying mechanism, I have devised a carrier wheel generally 45 designated at D, which consists in this instance of looped rods bent into the form of a segment 225 of a cylinder with the ends of the rods being held in a plate 226, the said plate having a collar by which it is attached to a rotatable 50 shaft 227, this shaft being journaled on the frame in the bearings 236 and 237. Spaced inwardly of the loops 225 is another series of loops 225' held in the plate 226' in the same manner as just described, thus resulting in a carrier wheel 55 of segmental construction, which has radially extending slots adapted to receive an envelope and transfer it from one working station to another. Mid-way between the plates 226 and 226' is another plate consisting of semi-circular 60 components 229 and 229' which are removably attached to a plate 228 by means of bolts and nuts, or other securing means. Various sizes of the semi-circular plates can be used, depending upon the size of the envelope to be operated 65 upon. Vertical guides are formed at the sides of the carrier wheel and consist of the cross bars 239 and 239', the last named bar being held at one end in suspended relation by the link 268 which is attached to the frame at 269, 70 the said link engaging a transverse shaft 264 upon which one end of the bar 239 is supported in the same manner. At its opposite end the bar 239' is similarly journaled on a shaft 265 and said shaft is held in position by the link 75

266, this link being secured by the nut and bolt 267. A series of semi-circular loops are received in the bar 230 and at the opposite side another series is shown to consist of the loops 5 231, 232, 233 and 234. These loops may be removably received in the bars 230 and 230' so that as the size of the envelope varies, the size of the guide may be varied. At one end of the shaft 227, a ratchet wheel 235 is mounted 10 for engagement with a pawl 250 secured on the end of a rod 241, this rod 241 being adjustable in length by means of the turnbuckle 242 and being held in positive engagement with the ratchet wheel 245 by means of the spring 247, 15 which is attached at its opposite end to the bolt 248. The spring 247 is caused to act in the desired direction by extending over a sleeve 240 which encircles a pin 239, the outer end of said pin being held in fixed position by the plate 238, 20 which is mounted on the shaft 227.

The rod 243 has a pivotal connection 244 with a lever 245, this last named lever being connected to a shaft 246 and the shaft having in turn another oppositely extending lever 256 with 25 a pivotal connection 257 to the rod 258. The rod 258 connects by a turnbuckle 259 to an elongated rod 260 having a forked end 261 to which a roller 262 is attached, this roller engaging a cam 263 on the shaft 19. Obviously, movement 30 of the shaft 19 tends to impart reciprocation of the rods 260 and 241 whereupon the carrier wheel is moved intermittently.

FASTENER FEEDING AND PERFORATING MEANS

35 "E"

The fastener feeding means consists of a magazine 291 in which a stack of fasteners or staples are received, and these fasteners are removed one by one, perforated and then allowed 40 to drop through a slot, the end of which is provided with fingers which allow the fastener to be removed by a device to be described more in detail hereinafter.

45 A shaft 287 extends transversely of the frame of the apparatus and in the same vertical plane as that of the previously described magazine, this shaft having a divided wheel consisting of the segments 288 and 288' mounted thereon for rotation in a clockwise direction as viewed in Fig. 20. Transverse peripheral grooves 289 are provided in each of the divisions of the wheel for the reception of a single fastener from the stack of fasteners, these grooves being spaced 50 90° apart and serving to transfer the staples from the stack to the perforating station. Rotation of the shaft 287 is obtained from the shaft 19 through the sprocket 276, chain 277, sprocket 278, which revolves on the shaft 279, another 55 sprocket 280 mounted on the same shaft, movement of this sprocket tending to move the sprocket 282 mounted on the shaft 284 through the medium of a chain 281. The shaft 284 extends transversely of the apparatus and has a pinion 285 mounted thereon which meshes with the gear 286, said gear being fixed to the shaft 287. 60

65 After the divided wheel 288 has transferred the staple from the magazine to the perforating station, a means of support must be provided for the staple during such perforation. Such a means is shown in detail in Fig. 19 wherein a shaft 315 is illustrated having small prongs 316 and 317 fixed thereto and extending in such a manner as to engage the staple or fastener, the 70 movement of these prongs being controlled by

the bent lever 312 shown in detail in Fig. 21. This bent lever engages the projections 308, 309, 310 and 311, such engagement being maintained by means of the spring 313 which has a connection 314 to the frame. It will be understood, of course, that as the shaft 287 revolves reciprocation of the prongs 316 and 317 will be obtained.

The prongs 316 and 317 prevent the fastener from falling, but some means must be provided for maintaining the fastener with its web in 10 a vertical plane. Such means are shown in the guides 336 and 336', the description of one of which will suffice as they are formed in exactly the same manner. The guide 336 is pivotally mounted to the strap 335 by a pivotal 15 connection 337, there being a set screw 339 regulating inward movement of the guide, and a spring 338 maintaining the guide in fixed relation. A lip 340 is formed on the guide so that prongs of the fastener are prevented from turning, and thus the fastener is held in a vertical plane. By means of the pivotal connection 337 and the set screw 339, it will be readily apparent that the guide may be easily adjusted for various sizes of fasteners. 20

25 Thus far it will be seen that the fastener is held from falling into the slot and that guides maintain it in one plane so that now it is ready for perforation. This is obtained by means of a piston 323 mounted in the bore 322 of a barrel 30 321, this piston having a pair of prongs 324 and 325 extending from one of its ends, the other end being reduced and having a coil spring under compression mounted thereon, the said spring engaging a washer 328 and tending to retract the 35 piston at all times.

The piston is actuated by means of a rounded hammer head 329, the said head being mounted in one arm 330 of a bell crank which is loosely mounted on shaft 331. The other arm of the bell 40 crank 332 has a roller 333 mounted thereon for engagement with a cam 334, this cam being fixed to the shaft 284. From this description it will be seen that as the shaft 284 revolves the piston is actuated and the prongs 324 and 325 45 will perforate the fastener.

An anvil, or a means for backing up the fastener as it is being perforated, is provided by the head 304, which is a part of the bell crank 308, there being slots 302 and 303 in said head for 50 the reception of the prongs 324 and 325. The other end 305 of the bell crank has a roller 306 mounted thereon for engagement with the cam 307 which is secured to the shaft 284, the bell crank being rotatably mounted on the shaft 304. 55 It will be seen that the head or anvil will be forced into position just prior to the actuation of the piston 323, and that this is accomplished by means of the spacing and contour of cams 307 and 334. 60

Immediately after the perforating operation, a finger 345 (Figs. 20 and 23) descends and engages the prongs S2 and S2' of the fastener. The finger 345 has a bent portion 341 bolted to a small transverse shaft 342, said shaft being rotatably received in the standards 343 and 344. The shaft 342 extends beyond the standard 343 and has an arm 347 attached to its end, there being a roller 349 mounted on the end of said arm and engaging a cam 350 on the shaft 284. From 70 this it will be seen that as the shaft 284 revolves, the finger 345 reciprocates up and down and pushes the fastener S into the slot or conduit 353. The slot 353 has an enlarged entrance and is made up of a flat piece of sheet metal 353 and 75

two L-shaped side guides 351 and 352. The side guides have their lowermost ends formed into retaining fingers 356 and 357 which are adapted to engage the web S1' of the fastener. Additional 5 fingers 354 and 355 are placed on the guides and these fingers engage the prongs S2 and S2' so that the fastener is held with its prongs extending in a horizontal direction, and its web extending vertically in readiness to be engaged by a 10 fastener holder.

FASTENER APPLYING MEANS

"F"

15 After perforating the web of the fastener it is now ready to be applied to an envelope, and I prefer to apply it and then to clinch it rather than attempt to do both acts in one operation. Of course, it will be understood that in some instances it is not always necessary to clinch the fastener and that the application thereof may be modified so that one operation will serve.

The fastener S is removed from the above described slot fingers by means of a holder 366, 25 which comprises a member having two prongs 371 and 373 which engage the perforations in the web of the fastener. These prongs have enlarged end portions 372 and 374 with coil springs 377 and 375 held under compression and engaging 30 said ends respectively. The springs in turn are held in place by the small plugs 376 and 378, which not only serve to hold the springs in place, but will additionally serve to adjust the tension of the springs. The holder 366 is rectangular and 35 has a circular flange 369 seated in a recess 370 of a depending flange 386. The holder has a cylindrical portion 368 adjacent the flange 369 and this cylindrical portion is received in a corresponding bore of the end 367 of the flange 386.

40 The flange 386 depends from the cross arm 387 and this arm is slidably supported upon a pair of rods 392 and 393 by means of perforations 394 and 395 in its respective ends 388 and 389. A pair of rods 390 and 391 of smaller diameter than 45 the before mentioned rods 392 and 393 are rigidly attached to the ends 388 and 389, and constitute the means whereby movement is imparted to the cross arm and its depending mechanism. A fixed cross arm 396 connects the ends 50 of the large rods 392 and 393 and this cross arm has a corresponding depending central portion 397 which acts as an anvil for the fastener holder 366. The anvil 397 has rivets 398 and 399 with hardened head portions 400 and 401 which serve 55 to bend the prongs S5 outwardly so that the holder is held to the envelope and is now ready to be clinched thereto.

The means of supporting the fastener applying mechanism comprises the rods 392 and 393 60 which have their ends supported in the journals 408 and 407, respectively, in a manner permitting movement about the shaft 279. In order to move the cross arm 387 along the rods 392 and 393 a pair of sliding L members 410 and 409 are 65 provided which have the rigid connections 390 and 391 with the cross arm 387. These L members have a transverse connection 411 with a roller 413 revolvably mounted thereupon for engagement with the cam 414, said cam being rotatably mounted upon the shaft 279 and moving therewith. As a result of this construction it will be seen that the cam will impart reciprocating movement to the cross arm 387, which in turn will permit the application of the fasteners to an 70 envelope. In order to assure constant engage- 75

ment of the roller 413 with the cam 414 a pair of springs 415 and 416 are mounted so as to exert a pull upon the fastener applying frame toward the said cam.

So far the cam 414 has been described as a 5 means of moving the fastener applicator in one direction, but it is to be understood that the assembly of rods and cross arms has likewise imparted to it restricted circular or oscillating movement. The two extremes of this movement 10 are shown in Figs. 9 and 10, the former showing the station at which the fastener is received by the holder 366 and the latter illustrating the station at which the fastener is applied to the envelope. The fastener applying means being 15 of considerable weight must be supported in a balanced state, and this is brought about by providing a spring 426 which is attached to the extension 418 of the cross arm 396, this spring having a tendency to lift the fastener applying 20 means. In order that the said means be lifted, a connecting rod is attached to the extension 418, and this connecting rod comprises the rod 419 attached at its one end to the extension 418 and having a headed portion 420 25 at its opposite end. A spring 422 encircles the lower end of the rod 419 and this spring bears against a connecting member 421 to render the connecting rod slightly resilient. The opposite end of the connecting member has a pivotal connection 423 with an arm 421 rigidly attached to and rotatable with the shaft 19. Obviously, when the shaft 19 is rotated, the fastener holder assembly will oscillate about the shaft 279.

In order that the fastener may be expeditiously 35 applied to the envelope, a finger is provided which engages and opens the envelope so that the anvil may be readily received within the said envelope. This opening means consists of a bent member 440 carried on the fixed cross arm 396 which engages the flap N1 of the envelope as the cross arm assembly descends. Such finger pushes lightly against the envelope making possible the easy insertion of the anvil 397. The immediately preceding description illustrates a manner in 45 which a fastener is taken from the end of the slot 353 and applied to an envelope, the means for opening the envelope being also included in this description.

PATCH APPLYING MEANS

"G"

The envelope at this point has been printed and has had a fastener applied thereto and is 55 now ready to have its flap perforated, and to have such perforated portion of the flap reinforced by a patch. The mechanism for obtaining this result is mounted closely adjacent the fastener applying mechanism and works in conjunction 60 therewith. It consists of a means for applying water to a previously glue-coated surface of paper or cloth tape, cutting this tape into individual patches, perforating the patch and the envelope and simultaneously applying the patch to the envelope.

The water for moistening the glue is contained in a receptacle 456 having a hose connection 457 which has its other end received upon a moisture 65 70 75 80 85 90 95 100 105 110 115 120 125 130 135 a spring engaging it so as to insure proper engagement of the dog with the notches 448. The operating means described are mounted in a pivotal manner on a standard 453, said standard also having a locking dog 449 mounted thereon and the periphery of the wheel 447 is serrated in order to prevent slippage of the tape 464 between the wheel 447 and the wheel 463.

If, for any reason, the carrier wheel should fail to contain an envelope as a slot arrives at the fastener applying station, it is desirable to prevent the above described taping mechanism from functioning. More specifically, if there is no envelope in the vertical slot of the carrier wheel D in Fig. 10, it is well to prevent the tape from reaching the cut-off position because then the tape would be stuck to the machine and, as a consequence, the machine will have to be stopped and the tape scraped off, all of which would cause costly delays. As a means of avoiding such delays, I have provided a tripping finger 438 which is pivoted at 439 to an upstanding lug on the fixed cross-arm 396. A link 435 connects the finger 438 with a small bell crank pivoted to the standard 431. The link 435 is connected to the arm 434 of the bell crank, the other arm 433 of the bell crank normally lying below the link 445 which is the actuating link for the tape applicator. In the event that the finger 438 fails to engage an envelope, the arm 433 of the bell crank will be moved upwardly which, in turn, moves the link 445 upwardly and prevents the dog 446 from engaging the notched wheel 447. Thus it will be seen that if no envelope is contained in the slot, no tape will be cut off and applied to the machine. A receptacle 455 is provided to receive any drippage of the wheel 447 in the event that too much water is applied to the said wheel. The wheel 447 is fixed to the shaft 454 and said shaft has a small cog wheel 460 at one end thereof, which engages a smaller cog wheel 461 on the shaft 462 in order to revolve the coating roller 463. From this it will be seen that the tape is smoothly and efficiently fed into the applying and perforating mechanism.

The tape enters the slot 470 which is formed in a manner permitting separation of the end of the tape into the desired size of patch. This formation is obtained by inserting the upper end of the finger 473 in a slot larger than that desired and then backing the end 472 with a plate 471, all of which is secured to the depending member 469, the upper end of the finger 472 being reduced in width at a point adjacent a cutter 478 on the sliding member 477. A sliding abutment 475 is provided which is resiliently held in position by means of the spring 476 so that as the sliding member 477 contacts with the depending member 469, the abutment retracts. A perforating piston 479 is mounted in the sliding member 477 and this piston has a diameter slightly less than that of the hole 480, there being a surrounding inset portion 481 about said hole to provide a cutting edge with the piston. A transverse plate 483 is located immediately adjacent the sliding member 477 and to the rear thereof, and this plate receives the reduced end 482 of the piston 479 and also has two other rods 484 and 491 received therein, each of the said last named rods having coil springs 485 and 492, respectively, which tend to push the plate away from the tape.

In order to push the plate and its attendant mechanism against the action of the springs, a

hammer 500 is mounted for cooperation with the bolt head 491, this hammer being received on an L member 501, which, in turn, is locked by the set screw 504 to the member 502. The member 502 is, in turn, locked to the shaft 411, so that, as the shaft 411 reciprocates, due to the action of the cam 114, the hammer 500 likewise reciprocates and forces the sliding member 477 and piston 479 to the left as shown in Fig. 18. The envelope flap is received between the fingers 473 and 474 and as the sliding member 477 starts across the cutter 478 removes a patch, whereupon the patch is applied to the envelope flap after which the head 500 overcoming the resistance of the springs 485 and 492 forces the small piston 479 into the bore 480, thus perforating both envelope patch and flap.

FASTENER CLINCHING MEANS

"H"

20

A means for clinching the fastener to the envelope is illustrated in detail in Figs. 12 to 15, inclusive, and comprises a supporting rod 519 which has at its lower end an anvil and mechanism for urging a hammer 525 against said anvil with force.

The rod 519 is capable of limited rotational movement about the shaft 279 due to its being received in the journal member 520 and this rotational movement is obtained by a series of links and levers in a manner to be now described. The shaft 284, which extends transversely at the upper portion of the apparatus frame, has at its one end an eccentric 509 to which a rod 510 is connected by the connection 511. The rod 510 at its opposite end 512 has a sliding connection with the lever 515 by means of a bolt received in the slot 514. This lever 515 is fixed to a shaft 331 and the shaft 331 has another lever 516 depending therefrom with which a link 517 is pivotally connected, the last named link, in turn, being pivotally connected to another link 518 fixed to the upper end of the rod 519. As a consequence of such construction, it will be seen that movement of the shaft 284 will impart reciprocating motion to the anvil 541.

The drive for the anvil having been described, the clinching means will now be taken up in detail. At the lower end of the rod 519 a socket 521 is secured thereto in some such manner as welding, and this socket has a plate 522 integrally attached thereto and extending in a plane parallel to that of the axis of the rod 519. This plate may, of course, be an integral part of the socket, or may be welded or otherwise secured thereto. The plate 522 has at one end a pair of parallel projections 523 and 524, each of which has a bore in which a hammer 525 is received. This hammer has a reduced central portion 526 about which a coil spring 528 is wound, and one end of the hammer has an enlarged portion 527 of a suitable diameter to engage a latch 529. The latch 529 has a pivotal mounting 530 upon the plate 522, and is controlled by a link 532 which has a pivotal connection 531 with said latch at one end thereof, and a fixed connection with an arm 534 at its other end, there being a spring mounted around said rod 532 to insure engagement of said latch with said lower hammer projection 527. The arm 534 is secured to a small rod 535 which extends upwardly in parallel relation with the rod 519 and has limited rotational movement imparted to it by means of a finger 536 engaging a projection 537 upon the cam 414. It will be obvious from an inspection of Figs. 9 and 10 that upon each revolu-

75

tion of the cam 414, the latch releases the hammer 525 so that it engages the anvil 541 with considerable force.

The anvil 541 is secured to a bearing member 542 by the bolts 543 and 544, thus allowing oscillating movement about the shaft 545 which supports the said anvil between the plate 522 and an outer smaller plate 548. The last named plate 548 is held in fixed position to the plate 522 by means 10 of the headed bolts 549 and 550. The anvil has at one end a journal 552 bolted thereto by headed bolts 553 and 553', and this journal has a shaft 554 received therein, about which an eye bolt 555 is rotatably mounted. The screw threaded end 15 556 of the eye bolt is received in a shoulder 557 of a connecting rod 558, this connecting rod having an oval opening 565 at its opposite end and a roller 566 mounted upon the extreme portion of said opposite end. The roller 566 engages a cam 567 20 which is fixed to the shaft 279, and the oval opening 565 encircles said shaft 279. As a consequence it will be perceived that upon each revolution of the shaft 279 and cam 567 the anvil 541 will oscillate about the small shaft 545, thus providing a 25 means of opening the envelope and inserting the anvil therein ready for the final clinching operation.

EJECTING MEANS

"I"

30 The envelope is now practically completed and ready to be removed from the machine. This is accomplished by the mechanism best shown in Fig. 7 and generally indicated at I. This mechanism comprises a bearing member 570 in which a shaft 571 is adapted to oscillate, and this shaft has an arm 572 fixed thereto with a spring 573 engaging said arm. Another arm 575 is fixed to the shaft 571 and extends at an angle to the 35 spring arm 572, this last named arm having a pivotal connection 576 with a bent rod 577, the opposite end of said arm being forked, the forks 578 thereof engaging the shaft 19. A roller 579 is mounted adjacent the forks in position to engage a cam 580.

Another arm 581 is fixed to the shaft 571, the opposite end of this arm being curved and normally resting at a point adjacent the carrier wheel axle. Upon each revolution of the shaft 50 19 it will be observed that the ejector 581 moves outwardly shoving before it the completed envelope.

The envelope

55 The envelope illustrated in Figs. 32, 33, 38 and 39 is an example of one type of article upon which my improved machine is adapted to operate. As shown, the envelope consists of a flap N1 adapted to receive a patch 434 and overlapping flaps N2 60 and N3 adapted to receive a fastener S, the lower flap N4 extending over the overlapping flaps N2 and N3 and adapted to receive printing matter. Of course, it will be understood that the flaps may be rearranged and the printing matter placed at 65 any desired point.

The fastener, as shown, is of the type having a central web with two circular portions S1 and S1', and two prongs S2 and S2', the web being adapted to be perforated whereupon prongs S5 70 70 are provided.

The tape is the conventional paper tape 464, one surface of which is coated with glue 467.

Operation of the machine

75 The operation of each sub-assembly has been

fully described in connection with the description of each sub-assembly but a brief description of the complete process will now be given.

One source of power is provided at A, which not only imparts economy to the process but likewise makes possible simultaneous operation of each 5 sub-assembly so that a series of envelopes will receive each of the several operations all at the same time.

The envelopes are deposited in the magazine B, 10 whereupon they are accurately aligned and fed into the printing press C from which they are received in the carrier wheel D. The carrier wheel is intermittently operated so that the slots therein receive one envelope and then move so that the 15 adjacent slot is ready to receive another envelope. As the carrier wheel revolves, staples or fasteners are fed from the feeding mechanism E down to the fastener applying mechanism F. At this station the envelopes are opened and the fastener 20 applied to the overlapping portions N2 and N3 of the envelope, and the envelope has the appearance shown in Fig. 33. The carrier wheel then moves through an arc equal to the arc of one of the carrier wheel loops at which time it is again 25 opened and has the patch 464 applied thereto, the patch and flap being simultaneously perforated with such application. The envelope now has the appearance illustrated in Fig. 38 and is ready 30 for the final clinching operation. The carrier wheel continues its movement until the envelope arrives at a point adjacent the clinching mechanism H. The anvil 541 now slides inwardly behind the flaps N2 and N3, whereupon the hammer 523 is released with considerable force and 35 clinches the fastener S to the envelope. After this final operation the envelope is quickly and easily removed from the carrier wheel by means of the ejector I and received upon a belt 589, ready 40 for conveyance to any desired point.

Conclusion

From the preceding description it will be noted that envelopes may be printed and have fasteners 45 attached thereto in an extremely expeditious manner, and that all of the operations incident to such printing and fastening applications will be automatic. In other words, the human hand performs no part in the process and as a result mistakes which inevitably occur by hand methods are 50 entirely obviated. It will also be especially noteworthy that the apparatus is especially adapted to the handling of such articles as paper envelopes, and that no gripping takes place which 55 is liable to injure the envelopes.

A further advantage of the invention described, is that the fastener mechanism operates smoothly and at the same rate of speed as the feed mechanism, which is not true as far as I am aware of 60 any machines of the prior art.

A still further advantage of my improved machine is that various sizes of envelopes, within a central web with two circular portions S1 and S1', and two prongs S2 and S2', the web being adapted to be perforated whereupon prongs S5 65 70 are provided.

The machine just described has a great many other important advantages among which are the prevention of smearing ink on the envelopes which causes waste; the prevention of applying tape when there is no envelope in the carrier wheel; and the provision of registering means which insures accurate placement of the printing matter on the envelope.

Other modes of applying the principle of my 75

invention may be employed instead of the one explained, change being made as regards the mechanism herein disclosed, provided the means stated by any of the following claims or the equivalent 5 of such stated means be employed.

I therefore particularly point out and distinctly claim as my invention:

1. In apparatus of the character described, the combination of means for removing the lowermost envelope from a stack of envelopes, means for printing said envelopes, with means for applying fasteners to said envelopes, there being a fastener feed means present comprising, a magazine, a divided wheel, having spaced transverse 10 grooves in its periphery, and a slot leading from a point adjacent said wheel to said fastener applying means.
2. In apparatus of the character described, the combination of means for removing the lowermost envelope from a stack of envelopes, means for printing said envelopes, with means for applying fasteners to said envelopes, there being a fastener feed means present comprising, a magazine, a divided wheel, having spaced transverse 15 grooves in its periphery, a slot leading from a point adjacent said wheel to said fastener applying means, and a fastener cutting means.
3. In apparatus of the character described, the combination of means for removing the lowermost envelope from a stack of envelopes, means for printing said envelopes, with means for applying fasteners to said envelopes, there being a fastener feed means present comprising, a magazine, a divided wheel, having spaced transverse grooves 20 in its periphery, a slot leading from a point adjacent said wheel to said fastener-applying means, and a fastener cutting means adapted to cut within the periphery a fastener held in one of said spaced grooves.
4. In apparatus of the character described, the combination of means for removing the lower-

most envelope from a stack of envelopes, means for printing said envelopes, with means for applying fasteners to said envelopes, there being a fastener feed means present comprising, a magazine, a divided wheel, having spaced transverse 5 grooves in its periphery, and a slot leading from a point adjacent said wheel to said fastener applying means, said slot having retaining fingers adjacent said fastener applying means.

5. In apparatus of the character described, in 10 combination, means for feeding envelopes, means for printing envelopes, means for receiving said envelopes and holding them in a position with their flaps uppermost, and means for applying fasteners to said envelopes, said last-named means 15 comprising an anvil, and a fastener holder, said anvil being fixed to a cross arm connecting a pair of oscillatable rods, said holder being mounted on a second cross arm movable upon said rods.

6. In apparatus of the character described, in 20 combination, means for feeding envelopes, means for printing envelopes, means for receiving said envelopes and holding them in a position with their flaps uppermost, and means for applying fasteners to said envelopes, said last-named 25 means comprising an anvil, and a fastener holder, said anvil being fixed to a cross arm connecting a pair of oscillatable rods, said holder being mounted on a second cross arm movable upon said rods 30 and having a pair of spring actuated guide pins adapted to project through apertures in said fasteners.

7. In an envelope machine, means for applying a patch to a perforated portion of an envelope 35 consisting of a tape feeding wheel having a serrated periphery, notches in said wheel, a link having a dog adapted to engage the notches in said wheel, a friction roller adjacent said wheel, and means present to render said link inoperative when there is no envelope in said machine. 40

LEWIS C. PEARCE.
